LOOM SHUTTLE

Carl D. Brown, Hopedale, Mass., assignor to
Draper Corporation, Hopedale, Mass., a corporation of Maine

Application January 29, 1936, Serial No. 61,367

4 Claims. (Cl. 139—217)

The present invention pertains to automatically threading loom shuttles, and more particularly to such shuttles embodying thread tensioning devices of the so-called spring clamp type.

- 5   Shuttles of the type mentioned are used, under certain well-known conditions, in bobbin changing looms. The shuttles are accordingly so constructed that the filling thread enters into the tension device automatically during the automatic threading of the filling into the delivery 10 devices of the shuttle. I find that the entering of the filling thread into the tension device is greatly facilitated if the inner edge of the thread contacting surface of at least one of the friction members is inclined from the thread entrance end of the tension device outwardly and toward the normal path of the filling thread at an acute angle to the direction in which the filling thread normally runs. I further find that if the inner 15 edges of the friction members are inclined, as aforesaid, adjacent the normal path of the filling thread through the tension device, any tendency of the filling thread to balloon and thus move laterally of itself along the friction members is greatly restricted. This restriction is objectionable in that so confining the filling thread to a very narrow path through the tension device causes the thread to wear grooves in the friction members.
- 20   The present invention provides, in a shuttle of the type mentioned, a spring clamp tension device wherein the inner edge of the thread contacting surface of at least one of the friction members is inclined in the proper direction to facilitate threading, while the inner edges of both thread contacting surfaces, adjacent the normal path of the filling thread, extend substantially at right angles to such path, thereby eliminating the aforesaid wearing of grooves in the friction members.
- 25   The preferred embodiment of the invention is illustrated on the accompanying drawing, of which:

Fig. 1 is a plan view of the thread delivery end 45 of the shuttle;

Fig. 2 is a view partly in elevation and partly in section as indicated by line 2—2, Fig. 1, but to a smaller scale;

Fig. 3 is a view in cross-section taken approximately on line 3—3, Fig. 2;

Fig. 4 is a view in elevation, and to an enlarged scale, of the friction members detached from the shuttle; and

Fig. 5 is a face view of one of the friction members of Fig. 4.

The shuttle shown on the drawing is comprised of a shuttle body 1 having a cavity 2 for receiving an automatically replaceable filling carrier such as bobbin 3, a threading block 4, and a side delivery eye 5. The shuttle body may be pro-

vided with a thread trapping wall 6 as more fully disclosed in patent to W. I. Stimpson, No. 1,985,960, granted Jan. 1, 1935.

The shuttle has a longitudinally extending thread passage 7 which is in alignment with the cavity 2. The thread passage, or as much thereof as is in the threading block 4, is defined by the rear wall 8 and the front wall 9 of the threading block. A guard or horn 10 projects from the front wall 9 outwardly and rearwardly, as in the said Stimpson patent. The term "outwardly" is herein used to mean in a direction from the cavity 2 longitudinally of the shuttle toward the tip, i. e., toward the right, Figs. 1 and 2. Other expressions denoting direction are applicable to the shuttle when the same is considered to be positioned in the loom.

The transfer to the shuttle of a new filling carrier occurs when the shuttle is boxed on the side on the loom toward which the delivery end 20 of the shuttle points, which is on the right side of the loom for the shuttle shown on the drawing. The end of the filling thread *f* prior to and after the transfer extends from the filling carrier longitudinally of the shuttle to a suitable 25 holder (not shown), as is well-known in the art. Shortly after the transfer the shuttle is picked (toward the left, Fig. 1). When the shuttle is picked the filling thread unwinds from the carrier and in so unwinding swirls about, or balloons, 30 thus passing beneath the horn 10 and into the thread passage 7. The shuttle is thereafter picked in the opposite direction, whereupon the filling thread slides forwardly and downwardly into the side delivery eye 5. The path which the filling thread thereafter occupies, that is, from the filling carrier through the thread passage 7, beneath the horn 10, and forwardly through the delivery eye 5, is the "normal" path of the filling 35 thread as such expression is herein employed. 40

The shuttle as thus far described is not of novel construction, the principal features of novelty of the shuttle shown on the drawing residing in the spring clamp tension device, to be described. The tension device is conventional in that it is comprised of a pair of friction members which are yieldingly pressed together to exert a slip-grip on the running filling. The friction members 11 and 12 are, however, of novel construction as will presently appear. 45

The members 11 and 12 are mounted in the threading block to extend transversely of the normal path of the filling thread. To this end the members may be slidably mounted on a horizontal pin 13 in the bottom of the threading block, the members then extending substantially vertically and being positioned adjacent the inner end of the thread passage. The friction members may be yieldingly pressed together by 50 any suitable usual means, such as tension spring 55

14 which may be positioned beneath adjusting screw 15 accessible from the outside of the shuttle or beneath adjusting screw 16 which is accessible only when the threading block is removed from the shuttle (see Fig. 3).

The tension device is open at its upper end to provide a thread-entrance 17 which is positioned a substantial distance laterally of the shuttle (in this instance vertically) from the aforesaid normal path of the filling thread. The upper ends of the friction members may be curved or flared as shown to more sharply define the thread-entrance and to facilitate the entrance of the filling thread into the tension device.

15 Each of the friction members 11 and 12 has a thread engaging surface 18 (Figs. 3 and 5) which is preferably flat from the thread-entrance 17 to the bottom of the tension device. The inner edge of the thread engaging surface of 20 at least one, but preferably both, of the friction members is constructed to lead or deflect the filling thread laterally of itself from the thread-entrance down into the tension device. To this end, said inner edge is inclined from the thread-entrance outwardly and toward the normal path 25 of the filling thread, the edge 19 being inclined outwardly and downwardly generally at an acute angle to the longitudinal axis of the shuttle. I find it to be desirable to make the inner edge portion 30 19 not straight but curved as shown.

The aforesaid inclination or curvature of the edge 19 terminates at a point which is an appreciable distance above the normal path of the filling thread. The inner edges of the thread 35 contacting surfaces of both of the friction members are straight for a substantial distance on both sides of the normal path of the filling thread, and at a right angle to such path. In the embodiment shown, the straight portions 20 40 of the inner edges of the friction surfaces are substantially vertical from the edge 19 to the lower ends of the friction members.

It will be apparent that when the shuttle is first picked after transfer the filling thread in 45 swirling about will be thrown into the thread entrance 17. Then, as the shuttle continues in its flight the inclined or curved edge or edges 19 will pull the filling thread downwardly into the tension device. I find that with the construction 50 shown the filling thread will assume its position in the tension devices at least as soon as it becomes positioned beneath the horn 10. The filling thread will move further downwardly into its normal path when it threads into the side 55 livery eye as above described.

The invention as above described provides a spring clamp tension device which threads quickly and easily but which, because of the right angle position of the edges 20, permits the filling 60 thread to move laterally of itself along the surfaces 18 and thus prevent the wearing of grooves in the latter. It may be added that the word "edge" as herein employed is not restricted to a sharp corner, the edges being preferably well defined but smooth or curved, as shown.

Having fully disclosed the preferred embodiment of the present invention, I claim:

1. An automatically threading loom shuttle having a cavity for a filling carrier, a threading 70 block having a longitudinally extending thread passage in alignment with said cavity, and a first pick tension device of the spring clamp type positioned in said thread passage, said tension de-

vice being comprised of a pair of friction members extending transversely of said thread passage and yieldingly pressed together to exert a slip-grip on the running filling thread, said tension device having an open thread-entrance end 5 positioned a substantial distance transversely of the shuttle from the normal path of the filling thread through said passage, the inner edge of the thread engaging surface of at least one of said members being inclined from said thread-entrance end outwardly and toward said normal path of the filling thread at an acute angle to the longitudinal axis of the shuttle, the inner edges of both of said surfaces on both sides of the normal path of the filling thread through said thread 10 passage being straight and at substantially a right angle to said path.

2. An automatically threading loom shuttle having a cavity for a filling carrier, a threading block having a longitudinally extending thread 20 passage in alignment with said cavity, and a first pick tension device of the spring clamp type positioned in said thread passage, said tension device being comprised of a pair of substantially vertical friction members yieldingly pressed together to exert a slip-grip on the running filling thread, the upper end of said tension device being open and being positioned substantially above the normal path of the filling thread through said 25 thread passage, the inner edge of the thread engaging surface of at least one of said members being inclined downwardly and outwardly from the upper end thereof to a point above said path of the filling thread, the inner edges of both of said surfaces on both sides of said path being 30 straight and substantially vertical.

3. An automatically threading loom shuttle having a threading block, said threading block having a path therethrough wherein the filling 35 thread normally runs, and a spring clamp tension device carried by said threading block, said tension device being comprised of a pair of friction members extending transversely of said path and yieldingly pressed together to exert a slip-grip on the running filling thread, said tension device having an open thread-entrance end positioned a substantial distance from said path transversely thereof, the inner edge of the thread engaging surface of at least one of said members being curved from said entrance end longitudinally outwardly and toward said path for the purpose described, the inner edges of both of said surfaces on both sides of said path being straight and at substantially a right angle to said path.

4. An automatically threading loom shuttle having a threading block, said threading block having a path therethrough wherein the filling thread normally runs, and a spring clamp tension device carried by said threading block, said tension device being comprised of a pair of substantially vertical friction members yieldingly pressed together to exert a slip-grip on the running filling, the upper end of said tension device being open and being positioned a substantial distance above said path, the inner edge of the thread engaging surface of at least one of said members being curved outwardly and downwardly from a said upper end to a point above said path, for the purpose described, and the inner edges of both of said surfaces being vertical and substantially straight from said point to a point materially below said path.

CARL D. BROWN.
